UNITED STATES PATENT OFFICE.

JOHN JONES, OF OREGON CITY, OREGON.

MINER'S CANDLESTICK.

SPECIFICATION forming part of Letters Patent No. 270,316, dated January 9, 1883.

Application filed September 25, 1882. (No model.)

To all whom it may concern:

Be it known that I, JOHN JONES, of Oregon City, county of Clackamas, State of Oregon, have invented an Improved Miner's Candlestick; and I hereby declare the following to be a full, clear, and exact description thereof.

My invention relates to a novel candle stick or holder specially adapted for the use of miners; and it consists of a prod or point pivoted or hinged in the end of a safeguard, and secured in position either in line or at right angles with said guard by a swinging clasp. The prod is pivoted with a hook near its point, and a spring-ring for the candle is secured to the device, all of which will hereinafter fully appear.

The object of my invention is to provide a candle stick or holder, which, when not in use, may be carried in the pocket, and when in use 20 may be readily inserted in any convenient timber or hung from a projecting point, and is therefore particularly adapted for use in mines.

Referring to the accompanying drawings, Figure 1 is a perspective view of my invention. Fig. 2 is a perspective view showing the prod at right angles to the guards.

Let A represent a curved guard, between the forward parallel ends of which is pivoted a long point or prod, B, sharpened at its end.

Upon one side of the guard A is pivoted a clasp, C. This consists of a channel-shaped piece, which is adapted to fit over and inclose the parallel ends of the guard A and the intervening rear end of the prod B, and thus 35 secure the latter whether it be closed up within the guard or be opened out and extended away from it. The clasp C is provided with notches c in each side, about its center.

D represents a ring or band formed of a 40 spring-strip, one end of which is secured to the forward end of guard A upon one side. Its

other end is loose and laps over the first end. The ring or band is thus adapted to increase its diameter when a large candle is inserted. It will spring around and hold any suitable 45 size of candle.

The forward end of prod B is provided with a hook, b, extending from one side at right angles, as shown.

The prod B, when the device is not in use, 50 is closed up within guard A, and is secured by clasp C. When it is to be used the clasp is turned back and the prod is opened out to extend directly forward, when it is again secured by the clasp. It is then driven into any 55 convenient timber or into the ground, or in any place where it will hold and sustain the candle upright, or it may be hung from a projecting piece of rock or from any suitable 60 place by turning the prod at right angles with the guard and turning the clasp down, which will fit its notches c about it and hold it securely. In this position it may be hung by the hook b, and the candle will still be upright.

Having thus described my invention, what I claim as new, and desire to secure by Letters Patent, is—

A miner's candle stick or holder, consisting of the guard A, pivoted swinging prod B, having a hook, b, near its point, swinging clasp C, securing the prod in line with the guard, and having side notches, c, fitting and securing the prod when turned at right angles with the guard, and the band or ring D, all arranged, 70 75 operated, and constructed substantially as herein described.

In witness whereof I hereinunto set my hand.
JOHN JONES.
